UNITED STATES PATENT OFFICE.

ALBERT B. DICK, OF LAKE FOREST, ILLINOIS, ASSIGNOR TO A. B. DICK COMPANY, OF CHICAGO, ILLINOIS, A CORPORATION OF ILLINOIS.

STENCIL-DUPLICATING APPARATUS.

945,264.

Specification of Letters Patent.

Patented Jan. 4, 1910.

Application filed February 19, 1909. Serial No. 478,855.

To all whom it may concern:

Be it known that I, ALBERT B. DICK, a citizen of the United States, residing at Lake Forest, in the county of Lake and State of Illinois, have invented certain new and useful Improvements in Stencil-Duplicating Apparatus, (Case B,) of which the following is a specification.

The invention relates particularly to that type of stencil-duplicating machines in which is employed a drum, having rotary or oscillatory movement, provided over part or all of its periphery with a foraminated stencil-carrier, outside which a waxed stencil-sheet is secured in position and to the interior of which the ink is supplied, such ink, on passing through said stencil-carrier and through the interstices in said stencil-sheet, being deposited upon impression sheets passing between the periphery of said drum and another member, such as an underlying pressure-roller.

Duplicating apparatus of this type as heretofore employed has been provided with ink by means of a brush, manually operated, to convey the ink to and distribute it over the inner surface of the stencil-carrier.

One of the objects of the present invention is to provide, chiefly for duplicating apparatus of this type, means for carrying the ink within the stencil-carrying drum, for depositing it upon the carrier of said drum, and for distributing it upon said carrier, either over the entire area thereof or at such portions as may be desired.

The invention is illustrated in the accompanying drawings, in which—

Figure 1 is a central longitudinal section of a duplicating machine of the rotary type, showing my improvement (in elevation) applied thereto; Fig. 2 is a central transverse section through the duplicator-drum, showing the inking apparatus herein to be described, partly in section and partly in elevation; Fig. 3 is a detail view illustrating the inking apparatus in inoperative position; Fig. 4 is a section on the line 4—4; Fig. 2; and Fig. 5 is an inverted plan view, showing one of the valves illustrated in Figs. 2 and 4.

Referring to these drawings, there are here illustrated the main frame-members having upwardly extending arms A, A', in which are carried stubs-shafts a, a', supporting the drum, which comprises the heads a², a³ con-

nected by tie-bars a⁴, a⁵, and having the stencil-carrier a⁶ of foraminated material, and ink-pad a⁷ over which the waxed stencil-sheet is secured in any suitable manner. Underlying the stencil-carrying drum, is the pressure-roller B mounted in hinged spring-pressed arms B' and controlled by throw-off mechanism including shaft b and eccentrics b'. These parts need not be further described in detail, since they form no part of the present invention.

C designates the ink-container, here shown as tubular in form, although obviously it may be of any suitable design. It is supported at one end by a bearing c formed therein, which receives the end of the stub-shaft a', and at the other end by means of a pin c' journaled in the stub-shaft a. The container C, having filling-port c², is here shown as provided with a member of hand-operated valves D extending through it, each in a housing d having therein a coil-spring d' surrounding the valve-stem d² connected at its upper end with finger-piece d³. Each of the valve-stems d² is provided at its lower end with a ball-and-socket joint d⁴, whereby it is connected to a double valve-head d⁵ coacting with ports d⁶, the ball-and-socket joint assuring tight closure of said ports, when the parts are in the position in which they are illustrated in Figs. 2 and 4. The valve-heads are shown as arranged within a downwardly-depending hollow extension E of the container casing, and, to prevent disarrangement, may be provided with ears e, e. There may, of course, be any number of valves and ports for the egress of the ink.

F designates an ink-distributing device, here shown in the form of a roller carried at its ends in arms f pivotally mounted at f' on a downwardly-projecting integral portion e' of the container casing. With one or both of said arms, is associated a spring f² exerting outward pressure upon said roller F. In the present case, I have shown such a spring f² at one end of the roller, and at the other end a catch for locking said roller in inoperative position, this comprising the arm f³ having a curved end adapted to coact with the shank of the screw f⁴ carrying the stencil-securing clamp or bail f⁵. The arm f³ is mounted upon the pivot f' and connected with a spring-arm f⁶ having finger-piece f⁷, said spring-arm having a notch coacting with one or the other of two pins f⁸.

The interior of the drum is provided with an offset shoulder f^9 . When the inking apparatus and the drum are moved relatively to each other, so as to cause the roller F to ride up on said shoulder f^9 , the roller is moved inward toward the axis of the drum, and the arm f^3 brought into coaction with the screw f^4 . In this position, the inking apparatus and the drum will move together. Upon moving the finger-piece f^7 and arm f^8 into contact with the pin f^8 , the arm f^8 is released from the screw f^4 , thereby again permitting the inking apparatus and the drum to move relatively to each other. The inking apparatus and the drum may be moved relatively to each other for the distribution of the ink in any suitable manner. Thus, particularly where, as in the present case, but a portion of the periphery 20 of the drum is covered by the stencil-carrier and stencil - sheet, said container may be grasped by the hand and oscillated so as to bring the roller F into contact with the stencil-carrier or any part thereof. Or, if desired, the inking apparatus may be locked in a fixed position and the drum partially rotated, back and forth, for the same purpose. In the drawings, I have shown a lock G secured by means of slot g and screw g' to 25 the rearward end of the ink-container. The upper end of said lock is provided with a slot which receives the stub-shaft a' , which does not rotate with the drum but is immovable relatively thereto. Said stub-shaft is provided with a notch, and with this coacts a lug g^2 formed upon the lock G. When, 30 therefore, the lock is in the position in which it is illustrated in Fig. 1, the ink-container is immovable relatively to the drum, in which case, after ink has been deposited 35 either upon the roller F or in advance of said roller, the drum may be partially rotated, to and fro, whereupon said roller will be brought into contact with the carrier as above described. The lock G is here shown 40 as provided with a downward extension g^3 making contact with an appurtenance of the roller (in this particular case, a portion of the spring f^2), to assure contact of the periphery of said roller with the internal 45 face of the stencil-carrier.

When the roller F rides up on the shoulder f^9 , the lock G is moved upwardly and the lug g^2 released from its coacting slot in the stub-shaft a' , thereby permitting the ink-containing and -distributing mechanism to move with the drum.

Having now described my invention, what I claim as new therein and desire to secure by Letters Patent is as follows:

1. In duplicating apparatus, the combination with a stencil-carrying drum, of a pivoted ink-container within said drum and having its major axis in the longitude thereof, and an ink-distributer within the

drum movable independently of said container into and out of engagement with the interior surface of the drum, substantially as set forth.

2. In duplicating apparatus, the combination 70 of a stencil-carrying drum, an ink-container pivotally mounted within the drum and having its major axis in the longitude thereof, an ink-distributer within the drum movable independently of said container into and out of engagement with the interior surface of the drum, and means for locking the distributer in inoperative position out of engagement with the drum, substantially as set forth.

3. In duplicating apparatus, the combination 75 of a stencil-carrying drum, an ink-container within the drum, an ink-distributer within the drum movable independently of said container into and out of engagement with the interior surface of the drum, a spring for pressing the distributer into contact with the drum, and means for locking the distributer in inoperative position out of engagement with the interior surface of the 80 drum, substantially as set forth.

4. In duplicating apparatus, the combination 85 of a stencil-carrying drum, an ink-container pivotally mounted within the drum and having its major axis in the longitude thereof, an ink-distributer within the drum movable independently of said container into and out of engagement with the interior surface of the drum, a spring for pressing the distributer into contact with the interior 90 surface of the drum, and means for locking the distributer in inoperative position out of engagement with the interior surface of the drum, substantially as set forth.

5. In duplicating apparatus, the combination 95 of a drum, an ink-container within the drum, an ink-distributer within the drum, and a pivotal support for the container and distributer permitting movement thereof circumferentially of the drum, said distributer 100 being movable independently of the container into and out of engagement with the interior surface of the drum, substantially as set forth.

6. In duplicating apparatus, the combination 110 of a drum, an ink-container within the drum, an ink-distributer within the drum, a pivotal support for the container and distributer permitting movement thereof circumferentially of the drum, said distributer 115 being movable independently of the container into and out of engagement with the interior surface of the drum, and a spring for pressing the distributer into engagement with the interior surface of the drum, substantially as set forth.

7. In duplicating apparatus, the combination 120 of a drum, an ink-container within the drum, an ink-distributer within the drum, a pivotal support for the container and dis- 125 trributer permitting movement thereof circumferentially of the drum, said distributer being movable independently of the container into and out of engagement with the interior surface of the drum, and a spring for pressing the distributer into engagement with the interior surface of the drum, substantially as set forth.

tributer permitting movement thereof circumferentially of the drum, said distributor being movable independently of the container into and out of engagement with the interior surface of the drum, and means for locking the distributor in inoperative position out of engagement with the interior surface of the drum, substantially as set forth.

- 10 8. In duplicating apparatus, the combination of a drum, an ink-container within the drum, an ink-distributer within the drum, a pivotal support for the container and distributor permitting movement thereof circumferentially of the drum, said distributor being movable independently of the container into and out of engagement with the interior surface of the drum, a spring for pressing the distributor into engagement 15 with the drum, and means for locking the distributor in inoperative position, substantially as set forth.

9. In duplicating apparatus, the combination of a drum, an ink-container pivotally mounted therein, means for detachably locking the container against rotational movement, and an ink-distributer mounted within the drum and movable into and out of engagement with the interior surface of the 20 drum, substantially as set forth.

10. In duplicating apparatus, the combination of a drum, an ink-container pivotally mounted therein, means for detachably locking the container against rotational movement, an ink-distributer mounted within the 25 drum and movable independently of said container, and a spring for pressing the distributor into contact with the interior of the drum, substantially as set forth.

- 30 11. In duplicating apparatus, the combination of a drum, an ink-container pivotally mounted therein, means for detachably locking the container against rotational movement, an ink-distributer mounted within the 35 drum and movable independently of said container, a spring for pressing the distributor into contact with the interior of the drum, and a locking means for locking the distributor in inoperative position, substantially as set forth.

- 50 12. In duplicating apparatus, the combination of a stencil-carrying drum, an ink-container within said drum, a shaft on which said container is pivotally mounted

permitting it to be rocked relatively to the 55 drum, an ink-distributer within the drum, means for supporting said distributor permitting movement thereof into and out of contact with the interior surface of the drum, and a spring for pressing the distributor 60 into contact with the drum, substantially as set forth.

13. In duplicating apparatus, the combination of a stencil-carrying drum, an ink-container within said drum, a shaft on which 65 said container is pivotally mounted permitting it to be rocked relatively to the drum, an ink-distributer within the drum, means for supporting said distributor permitting movement thereof into and out of contact 70 with the interior surface of the drum, a spring for pressing the distributor into contact with the drum, and means for locking said container against rotational movement relatively to the drum or releasing it to permit such movement at will, substantially as 75 set forth.

14. In duplicating apparatus, the combination of a stencil-carrying drum, an ink-container, an ink-distributer, a single means for 80 pivotally supporting the distributor and the container within the drum permitting rotational movement thereof relatively to the drum, said roller being movable into and out of contact with the interior surface of the 85 drum, and a spring for pressing the distributor into contact with the drum, substantially as set forth.

15. In duplicating apparatus, the combination of a stencil-carrying drum, an ink-container, an ink-distributer, a single means for pivotally supporting the distributor and the container within the drum permitting rotational movement thereof relatively to the 90 drum, said roller being movable into and out of contact with the interior surface of the drum, a spring for pressing the distributor into contact with the drum, and means for locking said container and said distributor against rotational movement relatively 95 to the drum or releasing them at will, substantially as set forth.

This specification signed and witnessed this 9th day of February, 1909.

ALBERT B. DICK.
